SEWING MACHINE

Norman V. Christensen, Chicago, and Hans Hacklander, Tinley Park, Ill., assignors to Union Special Machine Company, Chicago, Ill., a corporation of Illinois

Application June 12, 1936, Serial No. 84,862

2 Claims. (Cl. 112—63)

This invention relates to sewing machines; and it has reference more particularly to what are known as "feed off the arm" sewing machines wherein the work being sewed is advanced outward of a supporting arm incident to presentation to the stitching instrumentalities.

In sewing machines of the type specifically referred to relatively heavy rocker arms are ordinarily employed to convert the rotary motion of an actuating shaft into back and forth movement of the parts, such, for example, as the needle-carrying bars, which require reciprocation. The action of these rocker arms is attended by excessive vibration and results in rapid wear of said arms and in the parts connected with them.

Our invention is directed toward overcoming the drawbacks which have been pointed out, not only for the purpose of minimizing vibration and the rapid wear attendant thereupon, but of making it possible to safely operate the machines at much higher speeds than heretofore with a corresponding increase in productive output.

One way in which the foregoing advantages can be readily realized in practice will be evident from the following detailed description of the attached drawings, wherein

Fig. I shows the top plan view of a feed off the arm sewing machine conveniently embodying our invention, with the top cover plate of the machine removed and with portions of its frame broken away and sectioned to expose important parts which would otherwise be concealed.

Fig. II shows the front elevation of the machine, likewise with portions broken away and in section to expose certain parts at the interior.

Fig. III shows the elevation of the left hand end of the machine with its drive wheel and its work-supporting arm removed; and

Fig. IV is a transverse section taken as indicated by the arrows IV—IV in Figs. I and II.

As herein illustrated, the machine comprises a bracket-like frame 1 with a flat base 2 to rest upon a suitable table or other support, and with an integrally formed, forwardly-projecting longitudinal tubular portion 3 at an elevation above said base. Extending laterally from the tubular portion 3 of the machine frame at the left hand end, is a neck 4 which terminates in a vertical head 5, and pendant from the right hand end is a boss-like projection 6 whereto is secured a work supporting arm 7 which extends outward at an angle with its free end underreaching the head 5. By suitable feeding mechanism (not illustrated) within the hollow of the arm 7, the work being sewed in the machine is progressively ad-

vanced outward of said arm past the needles indicated at 8 of which there are two in the present instance. All the working parts of the machine derive their movements either directly or indirectly from a main shaft 9 which extends axially through the elevated tubular portion 3 of the frame 1 and which is journaled in suitably spaced inset bearing bushings 10, 11, 12, and 13. At its left hand protruding end, the shaft 9 is provided with a combined hand and belt wheel 15 so that the machine can be operated either manually or under power. Mounted on the shaft 9 near the right hand end are three eccentrics 16, 17 and 18, which, through the downward strap rods 19, 20 and 21 respectively associated with them, 15 actuate the feed mechanism already referred to, and a suitable complementary stitch-forming means (not illustrated) that cooperates with the needles 8 in a well known manner within the outer end of the work supporting arm 7. The usual presser foot of the machine is indicated at 22, and as shown is secured to the lower end of a presser bar 23 confined to up and down movement in guide bushings 25 and 26 at the top and bottom of the head 5. The presser bar 23 is 20 yielding urged downward by a leaf spring 27 which is anchored by a stud 28 (Fig. III) projecting upward from a boss 29 on the frame 1 and extending forwardly along the top of the neck 4 and into the head 5 through an opening 30 in the back of said head. The free end of the spring 27 reaches into a longitudinal slot 31 of the bushing 25 and bears directly upon the rounded top end of the presser bar 23 as shown in Figs. II and III. A means is shown in Fig. III at 32 whereby the 25 pressure of the spring 27 may be regulated. The presser foot 22 may be locked in elevated position, when required, by means of a cam latch 33 which cooperates with a lateral projection 34 of a collar 35 secured to the presser bar 23 within 30 the head 5. As shown in Figs. I and III, the projection 34 of the collar 35 is engaged between a pair of guide plates 36 respectively at opposite sides of a vertical slot 37 in the outer end wall of the head 5, to steady the presser bar 23 in its 35 up and down movements and at the same time prevent rotation thereof. In order that the presser foot 22 may be lifted in opposition to the spring 27 during the sewing, the machine is fitted with a pedal control means including a rock shaft 38 40 which extends into the back of the head 5, and at its inner end has an arm 39 with a stud 40 which engages a vertical slot 41 in an upward tongue 42 affixed to the projection 34 of the collar 35, said slot 41 permitting the normal up and 45

down movements of the presser bar 23, see Figs. I and II. A lever 43 at the outer end of the rock shaft 38 is pivotally connected to the upper end of a link 45 extending downward through a clearance hole 46 in the base 2 of the machine frame 1 to a control pedal, not illustrated. After common practice the machine is further provided with a number of tensioning devices 47, 48, 49 and 50 for the needle and looper threads used in the sewing, each of said devices including a pair of friction discs 51 (Fig. II) which are free on stems 52 anchored in the machine frame and which are subject to regulatable springs 53. A slide plate 55 (Fig. I) operated concurrently with the presser foot lifting mechanism, carries wedge projections 56 for engaging between the discs 51 of the devices 47—50 to relieve the tension on the threads.

Coming now to those features which constitute the subject of our invention, there is secured to the main shaft 9 immediately to the left of the bearing 11, a spiral gear wheel 57 which, through an intermeshing idler wheel 58, serves to drive a similar gear wheel 59 on a short parallel shaft 60 within the head 5. The shaft 60 and the shaft 61 of the idler gear wheel 58 are journaled in bearing bushings 62, 63, 64 and 65, the bushings 62 and 64 being set into the right hand side wall 66 of the head 5, and the bushings 63 and 65 into the wall of a supplemental gear housing 67 integrally formed with the head 5 beyond said side wall and communicating with a chamber 68 set apart within the neck 4 by a cross partition 69 which supports the bushing 11 of the main shaft 9, and a dividing partition 70 between said neck and head. From Fig. IV it will be observed that the chamber 68 has a depression 71 constituting a sump for oil which is splashed about by rotation of the gear 57 and thus carried to the gears 58 and 59 as well as to the bearings 11, 62, 63, 64 and 65 for the shafts 9, 60 and 61. The gears 57, 58 and 59 are accessible upon removal of the cover plates 72 and 73 respectively closing the front of the gear housing 67 and the top of the chamber 68. As shown in Figs. I and II, the left hand end of the shaft 60 extends through the bearing 62 into the hollow of the head 5, and has secured to it a dynamically balanced crank disc 75 whereof the small diameter pin 76 is coupled, by means of a relatively light vertical link 77, with a correspondingly small diameter lateral stud projection 78 of a collar 79 on a bar 80 which carries the needles 8, said bar being confined, like the presser bar 23, to vertical axial reciprocation by guide bushings 81 and 82 set respectively into the top and bottom of the head 5. The outer end of the stud 78 on the collar 79 is flattened at opposite sides, as at 83, and engages between a pair of vertical guide plates 85 secured to the inner side of the wall 66 of the head 5 (see Figs. I and II) to restrain the needle bar 80 against rotation and to take the lateral thrusts of the link 77. The various parts within the hollow of

the head 5 are readily accessible upon swinging aside of a frontal protection cover plate 86 which is attached by a thumb screw 87.

According to our invention, the gears 51 and 59 are made with comparatively small teeth differing in number by a few odd teeth from those of the intervening idler 58 so that the shock loads attendant upon the operation of the needle bar will be apportioned between the teeth of said gears and the wear correspondingly distributed.

As a consequence of the described construction, it will be apparent that the functioning of the needle bar actuating mechanism will be smooth, since the weight of the link 77 is compensated for by the balancing of the crank disc 75 and its lateral thrusts nullified through confinement of the stud 78 on the needle bar 80 to movement between the guide plates 85, and since the shaft of the crank 60 is coordinated with the drive shaft 9 through the rotary gear train 57—59, so that the sewing machine can be safely operated at high speeds without excessive noise and without vibration such as would result in rapid wear. The provisions made for self lubrication of the needle bar actuating mechanism preclude the necessity for any attention upon the part of the operator except for renewal or replenishment of the oil in the sump at very infrequent intervals.

Having thus described our invention, we claim:

1. In a feed-off-the-arm sewing machine, a frame having an elevated horizontal portion terminating in a hollow head, and a work supporting arm underreaching said head; a longitudinal drive shaft extending along the elevated longitudinal frame portion; a needle bar confined to vertical reciprocation in the head; a needle actuating shaft substantially parallel to the longitudinal shaft and journaled within the head; a train of gears connecting the needle actuating shaft with the drive shaft; operating connections within the head through which the needle bar is reciprocated from the needle actuating shaft; and partitioning within the head setting apart an oil chamber for the gear train to prevent splash oil from reaching the needle bar.

2. In a feed-off-the-arm sewing machine, a frame having an elevated hollow horizontal portion with a laterally-projecting hollow terminal head at one end thereof, and a work supporting arm underreaching said head; a longitudinal drive shaft journaled within the horizontal portion of the machine frame; a needle bar confined to vertical reciprocation in the head; a substantially parallel needle-actuating shaft in the horizontal plane of the drive shaft and journaled within the head; a train of gears connecting the needle-actuating shaft with the drive shaft; operating connections through which the needle bar is reciprocated from the needle-actuating shaft; and partitioning within the head setting apart an oil chamber for the gear train to prevent splash oil from reaching the needle bar.

NORMAN V. CHRISTENSEN.
HANS HACKLANDER.
